UNITED STATES PATENT OFFICE.

ERNEST DU PONT, OF WILMINGTON, DELAWARE, ASSIGNOR, BY MESNE ASSIGNMENTS,
TO FRANCIS I. DU PONT AND ERNEST DU PONT, BOTH OF WILMINGTON, DELAWARE.

EXPLOSIVE CHARGE FOR THE CENTRAL TUBES OF SHRAPNEL-SHELLS AND PROCESS OF PREPARING SAME.

1,207,884.

Specification of Letters Patent. Patented Dec. 12, 1916.

Application filed February 19, 1916. Serial No. 79,239.

To all whom it may concern:

Be it known that I, ERNEST DU PONT, a citizen of the United States, residing at Wilmington, county of New Castle, and State of Delaware, have invented a new and useful Improvement in Explosive Charges for the Central Tubes of Shrapnel-Shells and Processes of Preparing Same, of which the following is a full, clear, and exact description, reference being had to the accompanying drawings, which form a part of this specification.

Pellets for the central tubes of shrapnel shells are usually made in the form of axially perforated cylinders composed of black powder. The pellets forming the charge for a single tube are assembled end to end and fastened together in some manner to facilitate their introduction into the tube. Various methods have been used for this purpose. One method now in use is to wrap in paper a set of the proper number required to fill a tube and insert them, paper and all, into the tube. Another method is to wrap the pellets in paper and empty them from the paper into the tube. In either method, pieces of fabric are pasted over the opposite ends of the set to keep the loose powder which is in the base of the shrapnel shell and in the head from getting into the central opening.

The objects of my invention are: to expedite the operations of assembling the pellets and filling the tube; to render the set of pellets waterproof, thereby preventing deterioration in transportation; and to permit the insertion within the tube of an imperfectly aligned set of pellets.

To aid in explaining my invention, I refer to the accompanying drawings, in which—

Figure 1 is a perspective view of one of the pellets. Fig. 2 is a view, in elevation, of a holder with a set of pellets mounted thereon. Fig. 3 is a longitudinal section of a set of pellets after the first treatment. Fig. 4 is a view, similar to Fig. 3, after the last treatment and inserted in the central tube of a shrapnel shell.

In carrying out my invention, I substitute, for the paper wrapping, a wrapping of explosive material, preferably collodion. To

apply this collodion wrapping I proceed as follows: The required number of pellets *a* constituting a charge for a single tube *g* 55 are strung on a straight wire *b* which, if desired, may be fixedly mounted on a holder *c*. The whole, with the wire in a vertical position, may then be dipped into a tank containing a collodion solution. The solution, 60 being somewhat thick, does not penetrate into the junctions *d* between adjacent contacting pellets, but forms a surrounding unitary skin or coating for the entire set. The collodion is allowed to dry before removal of 65 the pellets from the wire. Thus there is formed a continuous, flexible, closely fitting tube *e* of nitrocellulose, which enables the set of pellets to be handled as a unit as if they were wrapped in paper. Two or three 70 dippings or coats may be applied, according to the strength of skin desired. After slipping the set of pellets from the wire, each end of the set is dipped in the said solution, which leaves a window *f* of nitrocellulose 75 over the central opening at each end. This prevents the loose powder that is in the base of the shrapnel shell and in the head from getting into this opening and dispenses with the necessity of securing a piece of muslin 80 over the ends, as is now customary.

In dipping the pellets while strung on a wire, instead of dipping them individually, several results are accomplished. First, the wire, and the close association of the 85 pellets while on the wire, prevents any windows being formed anywhere throughout the length of the set between its opposite ends. Second, the set of pellets is kept in alinement while the collodion skin is drying. 90 Third, this skin has some flexibility, so that in case there is some accidental disturbance of the alinement of the pellets, the flexibility of the skin permits the set to be pushed into the tube. The inclosure of the entire 95 outer surface of the set, including the two ends, in a skin of nitrocellulose, serves to effectively protect the charge from moisture, permitting transportation with less danger of deterioration than if wrapped in paper. 100

In place of a solution of collodion I may employ any liquid having the explosive and moisture-proof qualities of collodion and which is adapted, when dried, to set into

the form of a solid, but more or less flexible, enveloping skin or wrapper.

Having now fully described my invention, what I claim and desire to protect by Letters Patent is:

1. The process of preparing perforated pellets for the central tubes of shrapnel shells, which consists in assembling the same end to end in the relative positions they are to occupy in said tube and covering the peripheral surface of the set and opposite ends with a unitary flexible covering adapted to yieldingly hold the pellets in the relation in which they are assembled.
2. The process of preparing pellets for the central tubes of shrapnel shells, which consists in assembling the same in the relative positions they are to occupy in said tube and dipping the entire set in a solution of a substance adapted to dry and form a solid tube inclosing the set, thereby providing a charge capable of being handled as a unit.
3. The process of preparing perforated pellets for the central tubes of shrapnel shells which consists in stringing the same on a wire, and dipping the same in a solution of a substance adapted to dry and form a unitary tube inclosing the pellets and permitting them to be handled as a unit.
4. The process of preparing pellets for the central tubes of shrapnel shells, which consists in assembling the same in the relative positions they are to occupy in said tube, coating the surface of the same with collodion, and drying the same to form a unitary tubular container for the pellets.
5. The process of preparing perforated pellets for the central tubes of shrapnel shells, which consists in stringing the same on a wire, dipping the same in a solution of collodion and allowing the coating so formed to dry.
6. The process of preparing perforated pellets for the central tubes of shrapnel shells which consists in assembling the same in the relative position they are to occupy in said tube and coating the entire outer surface of the assembled set including the ends in a solution of a substance adapted to dry and form an enveloping solid container completely inclosing the set and permitting it to be handled as a unit in the tube-charging operation.
7. The process of preparing perforated pellets for the central tubes of shrapnel shells, which consists in stringing the same on a wire, dipping the same in a solution of a substance adapted to dry and form a unitary tube inclosing the pellets, removing the pellets and dipping the opposite ends of the set in the said solution.
8. The process of preparing perforated pellets for the central tubes of shrapnel shells which consists in assembling the same end to end, coating the peripheral surfaces

of the same with collodion to form a unitary containing tube for the entire set, and coating opposite ends of the set with collodion to form windows closing the alining central perforations of the several pellets against entry of loose powder.

9. The process of preparing perforated pellets for the central tubes of shrapnel shells, which consists in stringing the same on a wire, dipping the same in a solution of collodion, allowing the coating to dry, removing the pellets from the wire, and dipping the ends in a solution of collodion and drying to form windows closing the ends of the central perforation through the set.

10. The process of preparing sets of perforated pellets for the central tubes of shrapnel shells, which consists in dipping the set in a solution which upon evaporation leaves a skin of explosive material, and during said dipping preventing the entrance of the solution into the central perforation, and after said dipping forming a film of explosive material over the two end perforations of the set, thereby preventing the formation of obstructing films anywhere throughout the set, but providing protecting films at the two ends.

11. As a new article of manufacture, a set of pellets for the central tube of a shrapnel shell, arranged end to end in the relative positions they occupy in said tube, and a unitary flexible covering inclosing the peripheral surface and opposite ends of the set of pellets.

12. As a new article of manufacture, a set of pellets for the central tube of a shrapnel shell, arranged end to end, and an inclosing tube composed of a substance applied thereto in solution and dried.

13. As a new article of manufacture, a set of perforated pellets for the central tube of a shrapnel shell, arranged end to end with their perforations in alinement and an envelop composed of a substance applied thereto in solution and dried, said envelop extending over opposite ends of the opening through the set and closing said opening against entry of loose powder from the shell.

14. As a new article of manufacture, a set of perforated pellets for the central tube of shrapnel shells inclosed in a tube of waterproof explosive material.

15. As a new article of manufacture, a set of perforated pellets for the central tube of shrapnel shells inclosed in a tube consisting of a material containing nitrocellulose.

16. As a new article of manufacture, a set of pellets for the central tube of a shrapnel shell, arranged end to end, and an inclosing tube of collodion.

17. As a new article of manufacture, a set of perforated pellets for the central tube of shrapnel shells contained in a tube and hav-

ing over the ends a film of explosive material.

18. As a new article of manufacture, a set of perforated pellets for the central tube of shrapnel shells inclosed completely in an envelop of waterproof explosive material. 5

19. As a new article of manufacture, a set of perforated pellets for the central tube of shrapnel shells inclosed completely in an 10 envelop consisting of a material containing nitrocellulose.

20. As a new article of manufacture, a set of perforated pellets for the central tube of a shrapnel shell, arranged end to end, and an envelop of collodion inclosing the 15 peripheral surface of the set and the end openings.

In testimony of which invention, I have hereunto set my hand, at Wilmington, Delaware, on this 16th day of February, 1916. 20

ERNEST DU PONT.
